(57) **CLAIM**

The ornamental design for a shoulder-mounted child harness, as shown and described.

DESCRIPTION

FIG. 1 is a perspective view of a shoulder-mounted child harness, showing my new design;

FIG. 2 is a front view thereof;

FIG. 3 is a rear view thereof;

FIG. 4 is a left hand side view thereof;

FIG. 5 is a right hand side view thereof;

FIG. 6 is a top view thereof; and,

FIG. 7 is a bottom view thereof.

The cross hatched pattern shown in FIGS. 1 through 7 is understood to be continuous throughout the surfaces to which it is applied.
